UNITED STATES PATENT OFFICE

107,485

DESIGN FOR A WOVEN FABRIC

James Howard Hoffman, New York, N. Y.

Application October 20, 1937, Serial No. 72,337

Term of patent 7 years

To all whom it may concern:

Be it known that I, James Howard Hoffman, a citizen of the United States and a resident of the city, county, and State of New York, have invented a new, original, and ornamental Design for a Woven Fabric, of which the following is a specification, reference being had to the accompanying drawing, forming part thereof.

The figure is a plan view of a woven fabric showing my new design.

I claim:

The ornamental design for a woven fabric, as shown.

JAMES HOWARD HOFFMAN.
